AXIAL TYPE PUMP

Walter Ferris, Milwaukee, Wis., assignor to The Oilgear Company, Milwaukee, Wis., a corporation of Wisconsin

Application November 19, 1952, Serial No. 321,476

20 Claims. (Cl. 103—38)

This invention relates to multiple piston axial type pumps for pumping liquid at high pressures, the liquid usually being employed to energize hydraulic motors. The pump includes a cylinder barrel or block in which the pistons and cylinders are arranged in one or more circular rows about a central axis and are usually parallel to each other and to the axis. In a pump embodying the invention, the cylinder block is non-rotatable, such as by being fixed to or forming part of the main frame, and the pistons are reciprocated at adjustable stroke by a driving plate or cam which is inclinable to and is fixed to rotation with a drive shaft the axis of which coincides with the axis of the cylinder block.

The present invention has as an object to provide a pump capable of discharging a larger volume of liquid at high pressures than the pumps which were heretofore commercially available.

Another object is to provide a machine of the above type with novel means for varying its displacement.

Another object is to provide a pump of the above type with improved means for transmitting motion between the shaft and the pistons.

Another object is to provide for such a stationary cylinder pump a rotating driving mechanism having an inclinable driving plate to actuate the pistons at variable strokes, with novel counter-balancing means to maintain the driving mechanism in dynamic balance.

Another object is to provide a machine of the above type with hydraulic thrust bearings to counterbalance, at least in part, the pumping forces and with novel means for supplying pressure liquid to the thrust bearings.

Other objects and advantages will appear from the description hereinafter given of a pump in which the invention is embodied.

The invention is exemplified by the pump shown in part schematically in the accompanying drawings in which the views are as follows:

Fig. 1 is in part an elevation of and in part a longitudinal vertical central section through a pump in which the invention is embodied, the plane of the view being indicated by the line 1—1 of Fig. 2.

Fig. 2 is a transverse vertical section taken on the line 2—2 of Fig. 1 but drawn to a larger scale.

Fig. 3 is a transverse vertical sectional view illustrating the trunnions for a counterbalance and also for a wobble plate which effects reciprocation of the pumping pistons in response to rotation of a drive shaft, the view being taken on the line 3—3 of Fig. 1 but drawn to approximately the same scale as Fig. 2.

Fig. 4 is a sectional plan view taken through the pumping portion of the pump on the irregular line 4—4 of Fig. 2.

Fig. 5 is a sectional plan view taken through the other end portion of the pump on the line 5—5 of Fig. 3.

Fig. 6 is an end view of the pump with a cover plate removed and illustrates the mechanism for shifting the valves which control the main flow of liquid to and from the pump cylinders, the view being taken on the line

2

6—6 of Fig. 1 but drawn to approximately the same scale as Fig. 2.

Fig. 7 is a view showing two check valves through which liquid may flow to and from a cylinder when the valve which controls the main flow of liquid to and from that cylinder is closed, the view being taken in the same plane as Fig. 1 but drawn to a considerably larger scale.

Fig. 8 is a view illustrating how each piston is connected to the wobble plate which prevents torque from being transmitted to the pistons, the view being taken in the same plane as Fig. 1 but drawn to approximately the same scale as Fig. 7.

Fig. 9 is a diagram of the hydraulic circuit in the pumping portion of the pump, only four of the pistons and the valves associated therewith being shown.

Fig. 10 is a view of the front face of the wobble plate, the view being taken on the line 10—10 of Fig. 1 but drawn to a larger scale.

Fig. 11 is a rear face view of an element which engages the front face of the wobble plate and functions both as a hydraulic thrust bearing and as a valve, the view being taken on the line 11—11 of Fig. 1 but drawn to approximately the same scale as Fig. 10.

Fig. 12 is a section taken through a part of the element shown in Fig. 11 and through a rocker which supports the element and is tiltable to vary the displacement of the pump, the view being drawn to approximately the same scale as Fig. 11 and taken in the plane indicated by the line 12—12 of Fig. 5 and also indicated by the line 12—12 of Fig. 11.

Fig. 13 is a developed face view of a liner through which forces are transmitted between the arcuate face of the rocker and a driving head through which rotation is transmitted from the drive shaft to the rocker and the wobble plate, the view being indicated by the arcuate line 13—13 of Fig. 12.

Fig. 14 is a section taken on the line 14—14 of Fig. 13.

Fig. 15 is a transverse sectional view showing a part of the mechanism for tilting the rocker and for also tilting in the opposite direction a counterbalance which is provided to neutralize the unbalanced centrifugal forces in the rocker and the wobble plate, the view being taken on the irregular line 15—15 of Fig. 1 but drawn to approximately the same scale as Figs. 2—6.

Fig. 16 is a longitudinal vertical sectional view showing the rocker and a part of the tilting mechanism, the plane of the view being indicated by the line 16—16 of Fig. 5 and by the line 16—16 of Fig. 15.

Fig. 17 is a section through a mechanism for applying spring force to the counterbalance, the view being taken on the line 17—17 of Fig. 5.

Fig. 18 is a section taken on the line 18—18 of Fig. 17.

Fig. 19 is a section through the driving head and certain adjacent parts taken on the irregular line 19—19 of Fig. 15 and showing the hydraulic motors for tilting the rocker and the counterbalance.

Fig. 20 is a longitudinal vertical section through the portion of the pump which is shown in elevation in Fig. 1, the view being taken on the irregular line 20—20 of Fig. 6 and showing a part of the mechanism for controlling the hydraulic motors shown in Fig. 19.

Fig. 21 is a fragmentary sectional plan view taken on the irregular line 21—21 of Fig. 20.

Fig. 22 is a transverse section taken on the line 22—22 of Fig. 20.

Fig. 23 is a vertical transverse section taken on the line 23—23 of Fig. 20 but drawn to a larger scale.

Fig. 24 is a diagram of the hydraulic circuit in the driving portion of the pump.

Fig. 25 is a diagrammatic view of the piston reciprocating mechanism.

Figs. 26A and 26B together constitute a sectional plan

view of a modified form of the pump shown in Figs. 1-25, certain parts being shown in full and certain parts being broken away or omitted. Fig. 26A is taken on the line 26A—26A of Fig. 28. Fig. 26B is taken on the irregular line 26B—26B of Fig. 30.

Fig. 27 is a face view of a hydraulic hold-up element which functions both as a valve and as a hydraulic thrust bearing, the view being taken on the line 27—27 of Fig. 26A.

Fig. 28 is a face view of a valve seat for the hold-up element shown in Fig. 27, the view being taken on the line 28—28 of Fig. 26A.

Fig. 29 is a transverse section taken on the line 29—29 of Fig. 26A.

Fig. 30 is a transverse section through the cylinder block taken in the plane indicated by the arrows 30—30 on Fig. 26B.

Figs. 31 and 32 are detail sectional views taken through the hold-up element and fragments of adjacent parts but drawn to a larger scale than the other views, the planes of the views being indicated, respectively, by the lines 31—31 and 32—32 of Fig. 27.

The pump illustrated is so large and the scale of the drawings is necessarily so small that some clearances and the sizes of some parts had to be exaggerated and some features, such as sealing means and bearings for rotating parts, had to be omitted.

FIGS. 1-25.

The pump shown in these figures is identical to the pump shown in application Serial No. 304,477 filed August 15, 1952 of which this application is a continuation in part.

General arrangement

The pump has the greater part of its mechanism arranged within a casing 1 which has an end head 2 rigidly attached to and closing its front end and a cylinder block 3 closely fitted in and rigidly attached to its rear end portion. In order to simplify the drawings, casing 1 has been shown as a unitary structure but actually it is made of separate parts which are rigidly secured to each other. Also, it is provided with one or more ports which provide access to the interior and which are closed by removable cover plates. Casing 1 is adapted to be mounted upon a reservoir 4 which has not been shown in connection with casing 1 but has been shown schematically in Fig. 9.

A drive shaft 5 extends through casing 1 upon approximately the horizontal centerline thereof and is rotatably supported by a bearing 6 carried by end head 2, by a bearing 7 carried by cylinder block 3 at the front end thereof and by a bearing 8 carried by cylinder block 3 at the rear end thereof, bearings 7 and 8 being spaced apart by a spacer tube 9 arranged upon shaft 5.

Cylinder block 3 has a plurality of cylinders 10 formed therein in a circular row concentric with shaft 5. A piston 11 is fitted in each cylinder 10 and is connected by a connecting rod 12 to a non-rotating thrust member or wobble plate 13 which is rockably supported at its center upon a stationary spherical bearing or hollow ball 14 the center of which is on the axis of shaft 5 and through which shaft 5 extends with sufficient clearance to prevent the shaft from contacting the ball. As shown, ball 14 is provided with an annular flange 14a which is rigidly secured to the front end of cylinder block 3. Wobble plate 13 is provided with an annular split bearing 13a which is closely fitted therein and has an internal spherical surface complementary to and closely fitted upon ball 14 to rock thereon. The means for lubricating ball 14 has not been shown as it forms no part of the present invention.

Rotation of wobble plate 13 is prevented by a universal joint the ring 15 of which has wobble plate 13 pivotally connected thereto at diametrically opposite points by two pins 16 as shown in Figs. 1 and 3. Ring 15 is pivoted at points spaced 90° from pins 16 upon two pins 17 (Figs.

3 and 5) arranged in the bifurcated ends of two arms 18 each of which is slidably supported in a bracket 19 carried by casing 1. The extended axes of pins 16 and 17 pass through the center of ball 14. In order to simplify the drawings and to provide space for reference numerals, brackets 19 have been shown as being radial and fixed to the inner periphery of the casing but actually they are arranged axially and are attached to the inner end face of that portion of the casing in which cylinder block 10 is fitted.

Wobble plate 13 is restrained from axial movement against the thrust of pistons 11 by a thrust member or rocker 20 which is arranged within a driving head 21. As will presently be more fully explained, rocker 20 and driving head 21 are fixed for rotation with shaft 5 and are restrained from axial movement. The forces which prevent axial movement of wobble plate 13 are transmitted through a hold-up element 22, which has been shown as engaging the flat front face of wobble plate 13 and which is arranged in a recess 23 extending into rocker 20 from the flat rear face thereof, and through a plurality of piston shoes 24 each of which is associated with a connecting rod 12 and bears against the flat rear face of rocker 20 radially outward from element 22. The front face of rocker 20 and the rear face of driving head 21 are cylindrical and are accurately machined to radii struck from the center of ball 14. Concavo-convex liners (not appearing in Fig. 1) are closely fitted between the cylindrical surfaces to transmit axial forces from one to the other and to permit relative radial movement therebetween.

The arrangement is such that rocker 20 may be swung about the center of ball 14 either upward or downward in respect to Fig. 1 to accurately adjusted positions at one side or the other of the neutral position shown in Fig. 1. Swinging rocker 20 away from its neutral position causes its rear face to be inclined to the axis of shaft 5 and to gyrate about the shaft axis as the shaft and rocker 20 rotate. Since shoes 24 and hold-up element 22 bear against the rear face of rocker 20, gyration of that face causes wobble plate 13 to pivot upon pins 16, ring 15 to pivot upon pins 17 and wobble plate 13 to wobble upon ball 14, thereby effecting reciprocation of pistons 11.

The pumping mechanism

Cylinder block 3 is circular in cross-section and is closely fitted in a bore 25 formed in the rear end portion of casing 1. Cylinder block 3 and bore 25 are tapered slightly so that block 3 can be inserted nearly to its final position in bore 25 and then rotated step by step during assembly of the pump and so that it can then be forced into bore 25 until a fluid tight seal is formed between it and the wall of bore 25.

As shown in Figs. 1, 2 and 4, each of cylinders 10 has a piston valve 26 associated therewith and the several valves are arranged in a circular row concentric with the row of cylinders 10. Each valve 26 is preferably fitted in a ported sleeve which is arranged in a bore formed in cylinder block 3 but in order to simplify the drawings each valve 26 has been shown fitted for reciprocation in a bore 27 which is formed in cylinder block 3 and has three annular grooves or ports 28, 29 and 30 formed in its wall. Each port 28 communicates through a passage 31 (Fig. 2) with one of the cylinders 10. Each port 29 communicates through a passage 32 with an annular passage 33 which is formed in the wall of the bore 25 in casing 1 and communicates with a passage 34 (Fig. 4) by means of which the pump may be connected to one side of a hydraulic circuit. Each port 30 communicates through a passage 35 with an annular passage 36 which is formed in the wall of bore 25 and communicates with a passage 37 (Fig. 4) by means of which the pump may be connected to the other side of the hydraulic circuit.

Valves 26 may be made large enough to permit cyl-

inders 10 to be filled with liquid from an adjacent reservoir in response to retraction of pistons 11 but the size of valve 26 and the forces required to reciprocate them may be considerably reduced if the pump is supercharged at a pressure, such as 35 p. s. i., which is relatively low but is high enough to obtain the necessary velocity of the liquid passing through the valves 26 on the intake side of the pump.

As shown schematically in Fig. 9, liquid for supercharging the pump may be supplied by an auxiliary pump 40 which draws liquid from reservoir 4 and discharges it through a channel 41, a selector valve 42 and either a channel 43 into passage 33 or through a channel 44 into passage 36. Since the pump may be employed in a differential hydraulic circuit, a low pressure relief valve 45 is connected to channel 41 and discharges into reservoir 4 so that whenever liquid is returned to the main pump in excess of the liquid required to fill cylinders 10, the excess liquid may be exhausted through relief valve 45.

Since the pressure required to supercharge the main pump is low, supercharge pump 40 may be of a constant displacement type and the liquid discharged by it in excess of the liquid required to fill cylinders 10 may be exhausted through relief valve 45. But preferably the supercharge pump is a "constant pressure" pump. That is, a pump which will discharge liquid at a predetermined maximum rate until it creates a predetermined pressure and then it will automatically reduce its displacement until it is delivering just enough liquid to maintain that pressure substantially constant, such as the supercharge pump shown in Patent No. 2,484,337.

Selector valve 42 includes a body 46 which is fastened to casing 1 and has an axial bore 47 and three annular grooves or ports 48, 49 and 50 formed in the wall of bore 47. Port 48 is connected by channel 41 to pump 40, port 49 is connected by channel 43 to passage 33 and port 50 is connected by channel 44 to passage 36. Communication between port 48 and ports 49 and 50 is controlled by a valve plunger 51 which is fitted in bore 47 and has two ducts 52 and 53 extending into it from its opposite ends and then extending radially outward into communication with ports 49 and 50 respectively.

The arrangement is such that, when high pressure is created in passage 33, liquid will flow therefrom through channel 43, port 49 and duct 52 to one end of bore 47 and will shift plunger 51 into the position shown and plunger 51 will open port 50 to port 48 so that liquid can flow from pump 40 through channel 41, selector valve 42 and channel 44 into passage 36 and, when high pressure is created in passage 36, liquid will flow therefrom through channel 44, port 50 and duct 53 to the other end of bore 47 and will shift plunger 51 into its other position and plunger 51 will open port 49 to port 48 so that liquid can flow from pump 40 through channel 41, selector valve 42 and channel 43 into passage 33.

Port 48 in valve 42 is also connected by a passage 54 to an annular passage 55 which extends around cylinder block 3 and has been shown as being formed in part in casing 1 and in part in cylinder block 3. Passage 55 is thus continuously supplied with supercharging liquid.

The mechanism for shifting valves 26 has been shown in Figs. 1, 4 and 6 as being arranged within a cylindrical housing 58 which is attached to the rear end of cylinder block 3 and is closed at its rear end by a cover plate 59. Each of valves 26 has a universal joint 60 fixed to its rear end and connected by linkage 61 to one of the several arms 62 of a valve actuator 63 which is journaled as by means of bearings 64 upon a tubular cam 65 which is fixed upon the rear end portion of shaft 5. The axis of the outer periphery of cam 65 is inclined to the axis of the inner periphery thereof so that actuator 63 is inclined to the axis of shaft 5.

Actuator 63 is pivoted at diametrically opposed points on its horizontal center line to a ring 66 by two pins 67. Ring 66 is pivoted at diametrically opposite points

5

on its vertical center line upon two pins 68 carried by two arms 69 which are supported in two brackets 70 carried by housing 58. The arrangement is such that, when shaft 5 is rotated, cam 65 will cause actuator 63 to pivot upon pins 67, ring 66 to pivot upon pins 68 and actuator 63 to wobble about the intersection of the axes of shaft 5 and pins 67.

Cam 65 is fixed upon shaft 5 in such a position that, when rocker 20 is adjusted to cause wobble plate 13 to be inclined to the axis of shaft 5 as previously explained, the plane of valve actuator 63 will be spaced 90° from the plane of wobble plate 13. The arrangement is such that, when the pump is pumping liquid and any piston 11 is at either end of its stroke, the valve 26 associated with the cylinder containing that piston will be in its closed position and will be blocking the port 28 leading to that cylinder as shown in Fig. 1. Instantly thereafter, both the piston and the valve start to move but the piston will be moving at its slowest speed while the valve will be moving at its highest speed so that the valve will quickly open port 28. The piston will accelerate and the valve will decelerate until the piston is at half stroke at which time the valve will be fully open as shown in Fig. 4. Then the piston will decelerate and the valve will accelerate until the piston reaches the other end of its stroke at which time the valve will have closed port 28 as shown in Fig. 1.

In Fig. 25 driving head 21 has been shown in the same position as in Fig. 1 but rocker 20 has been shown as having been swung downward in respect to Fig. 1 so that its rear face is inclined to the axis of shaft 5 and will gyrate about the shaft axis when shaft 5 and rocker 20 are rotated. The thrust of pistons 11 holds piston shoes 24 against the rear face of rocker 20 and thereby maintains wobble plate 13 parallel to the rear face of rocker 20. Two diametrically opposite points at which piston shoes 24 contact the rear face of rocker 20 have been indicated at A and B, point A being the contact point farthest from cylinder block 3 and point B being the contact point nearest to cylinder block 3.

With rocker 20 in the position shown in Fig. 25, the upper piston designated 11^x is at the end of its outstroke and its shoe 24 is in contact with the rear face of rocker 20 at point A. Cylinder block 3 contains an odd number of cylinders so that no two pistons are diametrically opposite each other but, for the purpose of this explanation, a piston 11^y has been shown diametrically opposite piston 11^x in Fig. 25 with the shoe 24 of the lower piston 11^y in contact with the rear face of rocker 20 at point B, in which position piston 11^y is at the end of its instroke.

When shaft 5 is rotated in the direction indicated by the arrow on Fig. 25, driving head 21 and rocker 20 will rotate with it and the rear face of rocker 20 will slide across the faces of the several piston shoes 24. During the first half-revolution of rocker 20 from the position shown in Fig. 25, its rear face will move the shoe 24 of upper piston 11^x rearward or inward harmonically until point B comes into alignment with that shoe at which time piston 11^x will have been moved to the end of its in-stroke or into a position corresponding to the position of piston 11^y shown in Fig. 25.

During the next half-revolution of rocker 20, its rear face will permit the shoe 24 of piston 11^x to be moved forward harmonically. If the pump is supercharged as shown, piston 11^x will be moved forward or outward by the supercharge pressure. If the pump is not supercharged, piston 11^x will be drawn forward or outward by wobble plate 13. In either case, piston 11^x will be moved forward or outward harmonically until point A comes into alignment with the shoe 24 of that piston at which time piston 11^x will have made a complete reciprocation and will be in the position shown in Fig. 25. Continuous rotation of rocker 20 will cause continuous reciprocation of the piston.

All of the pistons 11 are reciprocated in the same manner, the pistons whose shoes 24 are in contact with that half of rocker 20 which is the far half in respect to Fig. 25 being forced progressively rearward or inward and the pistons whose shoes 24 are in contact with that half of rocker 20 which is the near half in respect to Fig. 25 being moved progressively forward or outward.

As each piston 11 starts to move inward or rearward in its cylinder, the valve 26 associated with that cylinder will move in a direction to connect its port 28 to its port 29 and, as each piston 11 starts to move outward or forward in its cylinder, the valve 26 associated with that cylinder will move in a direction to connect its port 28 to its port 30. The inward moving pistons will discharge liquid from their cylinders through passages 31, ports 28, valve bores 27, ports 29 and passages 32 into annular passage 33 and thence through passage 34 to one side of an external circuit. The cylinders containing outward moving pistons will be supplied with liquid through passages 31, ports 28, valve bores 27, ports 30 and passages 35 from annular passage 36. Part or all of the liquid required to fill the cylinders may be supplied to passage 36 through passage 37 from the external circuit or a part or all of the liquid required to fill the cylinders may be supplied to passage 36 through passage 44, selector valve 42 and passage 41 from supercharge pump 40.

If rocker 20 is swung upward from its neutral position, the pump will function in the above described manner except that the movement of the pistons will be reversed, the pistons will discharge liquid into annular passage 36 and the cylinders will be supplied with liquid from annular passage 33.

When the pump is creating a high pressure and a piston starts to move inward, the liquid in the cylinder containing that piston is initially under a low pressure if the pump is supercharged, or it is under a negative pressure and the cylinder may not be completely filled with liquid if the piston has to draw liquid into its cylinder from a reservoir, but the discharge passage 33 or 36 contains liquid at the high pressure. Therefore, if each valve 26 opened the associated cylinder to the discharge passage at the instant that the piston in that cylinder started to move inward, the high pressure in the discharge passage would cause liquid to flow therefrom into the cylinder and cause a shock with resultant noise and energy loss. These shocks in pumps now in use often disintegrate the metal in the port walls.

In order to eliminate such shocks and noise, each valve 26 is so proportioned that it does not open the associated cylinder to the discharge passage until after the piston in that cylinder has moved inward far enough to create in its cylinder a pressure approximately as high as the pressure in the discharge passage and each cylinder is provided with an outlet check valve 71 through which the piston may discharge liquid before the valve 26 opens.

If the pump is reversible as shown, each valve 26 must be so proportioned that it will not open its port 28 to either its port 29 or its port 30 until after it has moved a predetermined distance in one direction or the other from its neutral position. In that case, it is preferred to provide each cylinder 10 with an inlet check valve 72 through which, as the piston in that cylinder moves outward during the first part of intake stroke, liquid may flow to the cylinder until the valve 26 associated with that cylinder has moved far enough to connect that cylinder to the passage 33 or 36 which at that time is the inlet passage. If such a check valve be not provided, the cylinder is temporarily starved at the beginning of the intake stroke, and gas may be formed in the liquid in the cylinder.

While any suitable type of check valve will suffice, check valves 71 and 72 preferably are so constructed that each may be readily inserted into and removed from cylinder block 3. As shown in Fig. 7, the check valves 71 and 72 for each cylinder 10 are arranged, respectively, in two

bore 73 and 74 formed in cylinder block 3 at the rear of that cylinder. Check valve 71 includes a body 75, which is threaded into bore 73 and has an axial bore 76 formed therein, and an annular valve seat 77 the opening 5 through which is concentric with bore 76 and communicates with cylinder 10. Bore 76 has a valve plunger 78 fitted therein and urged against valve seat 77 by a spring 79. Body 75 also has formed in its outer periphery intermediate its ends a cannelle 80 through which liquid may 10 flow to check valve 72 as will presently be explained. The inner part of bore 73 between body 75 and valve seat 77 communicates through a passage 81 with an annular passage 82 which is formed in casing 1 and extends around cylinder block 3. Suitable means are provided for subjecting the spring end of plunger 78 to the pressure prevailing in passage 82, such as a groove 83 formed in the periphery of plunger 78.

As shown in Figs. 1 and 9, annular passage 82 is adapted to be connected to either passage 33 or passage 20 35 under the control of an automatic selector valve 84 which is fitted in a bore 85 formed in a valve body 86 attached to casing 1. Bore 85 has three annular grooves or ports 87, 88 and 89 formed in the wall thereof. Port 87 is connected to passage 82 by a passage 90, port 88 25 is connected to passage 33 by a passage 91 and port 89 is connected to passage 36 by a passage 92. Valve 84 has two ducts 93 and 94 extending into it from its opposite ends and then extending radially outward into communication with ports 88 and 89 respectively.

30 The arrangement is such that, when high pressure is created in passage 33, liquid will flow therefrom through passage 91, port 88 and duct 93 into the left end of bore 85 and will move valve 84 against the right end of bore 85 in which position valve 84 will connect passage 82 to 35 passage 33 through passage 90, valve body 86 and passage 91 and, when high pressure is created in passage 36, liquid will flow therefrom through passage 92, port 89 and duct 94 into the right end of bore 85 and will move valve 84 against the left end of bore 85 in which 40 position valve 84 will connect passage 82 to passage 36 through passage 90, valve body 86 and passage 92.

45 Referring again to Fig. 7, check valve 72 includes a body 95 which is threaded into bore 74 and has a bore 96 extending into it from its inner end and a smaller bore 97 extending farther into it from the end of bore 96. A valve plunger 98 is fitted in bore 96 and is urged by a spring 99 against the shoulder formed at the junction of bores 96 and 97, thereby normally preventing flow of liquid from one bore to the other.

50 Valve body 95 also has two cannelures 100 and 101 formed in its peripheral surface and spaced from each other. Cannelle 100 communicates with cylinder 10 through a passage 102 and it communicates with the opposite ends of bore 96 through two sets of holes 103 and 104 respectively. Cannelle 101 communicates with bore 97 through a plurality of holes 105 and it is connected to supercharge passage 55 by a passage 106 which is intersected by bore 73 in the plane of cannelle 80.

55 The arrangement is such that the supercharge pressure, which is constantly maintained in passage 55, extends through passage 106, cannelle 101 and holes 105 into bore 97 and tends to move plunger 98 to open position but any pressure in cylinder 10 extends therefrom through passage 102, cannelle 100 and holes 103 into the spring end of bore 96 and assists spring 99 in holding plunger 98 in its closed position. When piston 11 is retracted, the pressure in cylinder 10 will drop until the 60 pressure in cylinder 10 is less than the force exerted upon plunger 98 by the supercharge pressure. Then the preponderance of force exerted upon plunger 98 by the supercharge pressure will move plunger 98 to its open position and liquid will flow from supercharge passage 70 55 through passage 106, cannelle 101, holes 105, bore 97,

holes 104, cannelure 100 and passage 102 into cylinder 10 and will fill cylinder 10 with liquid as fast as piston 11 is retracted.

Referring now to Fig. 9 and assuming that the pump is adjusted to cause pistons 11 to discharge into passage 33 as previously explained, the pistons 11 which are moving inward but are not near either the inner or the outer ends of their strokes are represented by the piston 11^a and the cylinder containing that piston and the valves associated therewith are indicated by their reference numerals with the exponent "a" added thereto. The pistons which are near the inner ends of their strokes are represented by the piston 11^b and the cylinder containing that piston and the valves associated therewith are indicated by their reference numerals with the exponent "b" added thereto. The pistons 11 which are moving outward but are not near either the inner or the outer ends of their strokes are represented by the piston 11^c and the cylinder containing that piston and the valves associated therewith are indicated by their reference numerals with the exponent "c" added thereto. The pistons 11 which are near the outer ends of their strokes are represented by the piston 11^d and the cylinder containing that piston and the valves associated therewith are indicated by their reference numerals with the exponent "d" added thereto.

During the in-stroke of a piston 11^a as indicated by the large arrow thereon, it will discharge liquid from its cylinder 10^a through passage 31^a, valve bore 27^a, passage 32^a and discharge passage 33 to the external circuit as indicated by the small arrows on those passages. At the same time, each piston 11^c is being retracted, as indicated by the large arrow thereon, and liquid is being returned from the external circuit into passage 36. Since pump 40 is maintaining pressure in passage 36 as indicated in Fig. 9 and as previously explained, the pressure in passage 36 will cause each cylinder 10^c to be supplied with liquid through passage 31^c, valve bore 27^c and passage 35^c from passage 36 as indicated by the small arrows on those passages, valves 26^a and 26^c being at this time open wide enough to permit liquid to flow freely from cylinder 10^a to passage 33 and into cylinder 10^c from passage 36.

Just before each piston 11 reaches the end of its in-stroke, the valve 26 associated with that piston closes, as indicated by the position of valve 26^b, and the piston continues to move inward as indicated by the full arrow on piston 11^b. After valve 26^b closes, piston 11^b will discharge liquid from its cylinder 10^b through check valve 71^b, passage 81^b, 82 and 90, valve body 86 and passages 91 and 33 to the external circuit, as indicated by the full arrows on those passages, until the contact point B (Fig. 25) on the rear face of rocker 20 comes into alignment with the shoe 24 on that piston at which time the piston is at the end of its in-stroke as previously explained.

Each piston 11 starts to retract, as indicated by the dotted arrow on piston 11^b, the instant that contact point B moves out of alignment with the shoe 24 of that piston. At the end of the in-stroke, some liquid at pump pressure remains in the cylinder and, if the cylinder were opened to the intake the instant that the piston started to retract as is the case in conventional pumps, the energy required to compress that liquid to pump pressure would be wasted. In the present case, the valve 26 associated with that cylinder remains closed until shaft 5 has rotated through a predetermined angular distance. During that time, the pressure in the cylinder reacts against the inclined rear face of rocker 20 and, the instant that contact point B on the rear face of rocker 20 moves beyond the axis of the shoe 24 of the piston in that cylinder, the liquid in the cylinder expands and assists in rotating shaft 5, thereby regenerating a large part of the energy required to compress to pump pressure the liquid remaining in each cylinder at the end of the instroke of the piston in that cylinder.

As soon as the liquid remaining in cylinder 11^b has expanded to such an extent that the pressure in cylinder 11^b is enough less than the supercharge pressure to permit check valve 72^b to open, liquid will flow from supercharge passage 55 through passage 106^b, check valve 72^b and passage 102^b to cylinder 11^b and keep it filled with liquid until shaft 5 has rotated through an angular distance great enough to cause valve actuator 63 to open valve 26^b and thereby permit the cylinder to be filled with liquid from passage 36 as explained above and as shown in Fig. 9 by the arrows which indicate the flow of liquid into cylinder 10^b.

Just before each piston 11 reaches the end of its out-stroke, the valve 26 associated with that piston closes, as indicated by the position of the valve 26^d, and the piston continues to move outward as indicated by the dotted arrow on piston 11^d. After valve 26^d closes, liquid is supplied to cylinder 10^d from supercharge passage 55 through passage 102^d, check valve 72^d and passage 106^d, as indicated by the dotted arrows on those passages.

Each piston 11 starts to advance, as indicated by the full arrow on piston 11^d, instantly after it reaches the end of its out-stroke but valve 26^d is closed at that instant so that piston 11^d cannot discharge liquid from cylinder 10^d until after it has created therein a pressure somewhat higher than the pressure in passages 33 and 82. Then check valve 71^d will open and piston 11^d will discharge liquid from its cylinder 10^d through check valve 71^d, passages 81^d, 82 and 90, valve body 86 and passages 91 and 33 to the external circuit, as indicated by the small full arrows on those passages, until piston 11^d has advanced a short distance and then valve 26^d will open and permit the piston to discharge liquid into passage 33 as explained above and as shown by the discharge of liquid from cylinder 10^a.

The piston and wobble plate assembly

Pistons 11 may be retracted either by supplying liquid to cylinders 10 at a sufficiently high pressure or by connecting pistons 11 to wobble plate 13 by suitable linkages such as the connecting rods 12. As shown in Fig. 8, each piston 11 has a spherical head 109 fixed to its outer end and fitted into a socket 110 formed upon one end of a short push rod 111 having a spherical head 112 formed upon its other end. Head 112 is fitted in a spherical socket 113 which has a shank 114 formed integral therewith and rigidly secured in wobble plate 13. An annular socket 115 is fitted upon the outer spherical surface of socket 113 and is connected to a sleeve 116 which encloses head 109 and socket 110 and has an annular inward flange 117 on its rear end. Flange 117 is engaged by a spring 118 which urges an annular spherical socket 119 against the rear face of head 109 and thereby prevents separation of ball and socket joint 109—110 and separation of ball and socket joint 112—113.

The arrangement is such that piston 11 may be drawn outward or forward by a retraction force transmitted thereto through its head 109, socket 119, spring 118, flange 117, sleeve 116 and sockets 115 and 113 from wobble plate 13, and piston 11 may be forced inward or rearward by a pumping force transmitted thereto through its head 109, rod 111, head 112 and socket 113. The pumping force is transmitted from rocker 20 to socket 113 partly through wobble plate 13 and partly through a shoe to be presently described.

In order to provide hydraulic thrust bearings in the ball and socket joints and to provide liquid for lubrication and other purposes, a recess 120 is provided between head 109 and socket 119, such as by flattening the end of head 109, and piston 11 is provided with an axial duct 121 which extends from recess 120 through piston 11 into communication with cylinder 10 into recess 120. A recess 122 is similarly provided between head 112 and socket 113 and is supplied with liquid through a duct 123 which extends

through ball 112 and rod 111 into communication with recess 120.

When pressure prevails in cylinder 10, liquid spreads over the spherical mating surfaces of the heads and the sockets and forms lubricating films therebetween. The area of each film into which pressure can extend should be limited and this may be accomplished by making socket 110 relatively short and by providing a suitably drained limit groove 124 in head 112. Any pressure in cylinder 10 will extend through duct 121 into recess 120 and through duct 123 into recess 122 so that the pressure in recesses 120 and 122 is the same as in cylinder 10. The pressure in the recesses will extend therefrom into the films of liquid between the mating surfaces of the balls and sockets. The film pressure at the edge of each recess will be the same as the pressure in the recess and will be substantially zero at edge of socket 110 and at the edge of groove 124. The liquid in each of recesses 120 and 121 acts as a liquid bearing between the ball and its socket and the area of each recess and the area of the film of liquid are such that the greater part of the pumping force is transmitted through the liquid in the recesses and the films containing pressure and only a small part of the pumping forces is transmitted through the films which have little or no pressure therein.

The pressure in the recess and in the film of liquid between each head and its socket tends to move the head away from its socket but the area of each recess and the area of the film containing pressure are so proportioned that the force exerted by the liquid upon each head is slightly less than the force exerted upon the inner end of the piston by the liquid in the cylinder.

A part of the pumping force required to advance piston 11 on a working stroke is transmitted from rocker 20 to socket 113 through the shoe 24 of that piston. Shoe 24 is arranged between the annular flat rear face of rocker 20 and the spherical head of a hold-up piston 126 which is fitted in an axial bore 127 formed in the shank 114 of socket 113. Piston 126 is hollow and has a spring 128 arranged therein to urge piston 126 against shoe 24 and shoe 24 against rocker 20. The contacting surfaces of rocker 20 and shoe 24 are made flat and smooth and the contacting surfaces of shoe 24 and piston 126 are made spherical and smooth to provide substantially liquid tight joints therebetween.

Shoe 24 is made annular to provide therein a pressure chamber 129, the interior of piston 126 is connected to chamber 129 through a passage 130 formed in the head end of piston 126 and bore 127 communicates through a passage 131 with recess 122 so that chamber 129 is continuously supplied with liquid at the pressure prevailing in cylinder 10.

When drive shaft 5 and rocker 20 are rotated, the rear face of rocker 20 will slide across the front faces of the several non-revolving shoes 24 and the liquid in the chambers 129 will provide liquid bearings between the shoes and the rocker. Also, liquid will seep from chambers 129 and provide a lubricating film between rocker 20 and the shoes. When rocker 20 is inclined to the axis of drive shaft 5 and is rotated, each piston will be progressively advanced during one-half of each revolution and will be progressively retracted during the other half of each revolution as previously explained. Each piston as it advances will create pressure in its cylinder and, since the same pressure prevails in chamber 129, that part of the pumping force which is transmitted from rocker 20 through shoe 24 is nearly all transmitted through the liquid in chamber 129 and only a small part thereof is transmitted through the film of liquid between the face of the shoe and the rear face of rocker 20.

Preferably, the area of each hold-up piston 126 is only about one-half the area of a pumping piston 11 so that only about one-half of the total pumping force is trans-

mitted through the shoes 24. The other part of the total pumping force is transmitted from rocker 20 through element 22 and wobble plate 13 to the shanks 114 of sockets 113. Element 22 functions both as a hydraulic thrust bearing and as a valve, as will presently be explained, and it is supplied with liquid from cylinders 10.

It has previously been explained that the interior of each hold-up piston 126 is supplied with liquid at the pressure prevailing in the associated cylinder. As shown in Fig. 8, the interior of the piston 126 in each shank 114 communicates with a passage 133 which extends through the wall of shank 114 and communicates with one end of a passage 134 which extends approximately radially inward therefrom and then extends axially through the front face of wobble plate 13 into communication with element 22.

The driving and hold-up mechanism

The outer ends of the several passages 134 are arranged in a circular row concentric with the axis of wobble plate 13 as shown in Fig. 10. Element 22 is fixed for rotation with rocker 20 and is provided with two arcuate grooves or ports 141 and 142 (Fig. 11) in axial alignment with the front ends of passages 134. Since wobble plate 13 is non-rotatable, rotation of element 22 with rocker 20 will cause the several passages 134 to register successively first with one and then with the other of ports 141 and 142.

Preferably, grooves 141 and 142 are formed in the rear face of element 22, a narrow annular wear plate is attached to element 22 and provided with two arcuate ports in registry with grooves 141 and 142, and a narrow annular wear plate is attached to the rear face of wobble plate 13 and has a hole extending therethrough from the end of each passage 134. But in order to simplify the drawings, the wear plates have been omitted and element 22 has been shown in Fig. 11 as having a narrow annular boss 143 formed upon its rear face and ports 141 and 142 formed in boss 143.

While element 22 is fixed for rotation with rocker 20, it is free to move axially within recess 23 and it is urged against wobble plate 13 by a hold-up motor 144 and a plurality of hold-up motors 144^a, each of which communicates with port 141 through a hole 145, and by a hold-up motor 146 and a plurality of hold-up motors 146^a each of which communicates with port 142 through a hole 147 so that motors 144 and 144^a are energized by liquid at the pressure prevailing in port 141 and motors 146 and 146^a are energized with liquid at the pressure prevailing in port 142. Hold-up motor 144 is arranged in element 22 at the center of port 141 and motors 144^a are arranged between motor 144 and the ends of port 141. Likewise, hold-up motor 146 is arranged in element 22 at the center of port 142 and motors 146^a are arranged between motor 146 and the ends of port 142.

As shown in Fig. 12, hold-up motor 144 includes a cylinder 148 which is formed in element 22, a piston 149 which is fitted in cylinder 148 and a spring 150 which urges piston 149 against the bottom of recess 23. Piston 149 has formed in its head end a hole 151 through which liquid may flow to other hold-up motors as will presently be explained. Since motor 146 is identical to motor 144 and motors 144^a and 146^a are exactly like motor 144 except that hole 151 is omitted from the pistons thereof, they have not been shown in detail.

Before explaining more fully how pressures are maintained in ports 141 and 142, it should be explained that driving head 21 has its body portion fixed for rotation with drive shaft 5, as by being keyed or splined thereto, that it has a circular front flange 21^a formed integral with the body portion, and that it includes an annular shell 21^b which is fixed to flange 21^a concentric with shaft 5 and extends around rocker 20 and ring 15 as shown in Fig. 3.

The rear end portion of shell 21^b has two pins 152 arranged therein at diametrically opposite points and the inner ends of pins 152 are supported in two diametrically opposed webs 21^c shown as being formed integral with shell 21^b. Pins 152 are arranged upon a common axis which extends through the center of ball 14.

Rocker 20 has two arms 20^a fixed thereto at opposite sides thereof and journaled, respectively, upon the two pins 152. When driving head 21 is rotated in response to shaft 5 being driven, rocker 20 will be rotated in synchronism with head 21 through pins 152 and arms 20^a. Rocker 20 is adapted to pivot upon pins 152 to change pump displacement as will presently be explained.

As shown in Fig. 11, the adjacent ends of ports 141 and 142 are spaced from each other and the unbroken surfaces of the spaces between the adjacent ends of the two ports cooperate with the front face of wobble plate 13 to form seals between the two ports. Element 22 is fixed for rotation with rocker 20 in such a position that a line passing through the axis of shaft 5 and through the centers of the spaces between the adjacent ends of ports 141 and 142 is at right angles to the common axis of pins 152. With element 22 in that position, one of the ports 141 and 142 always registers with the passages 134 which communicate with the cylinders 10 containing inward moving pistons 11 and the other one of the ports 141 and 142 always registers with the passages 134 which communicate with the cylinders 10 containing outward moving pistons 11. Consequently, one of the ports 141 and 142 is continuously supplied with liquid at pump pressure and the other one of the ports 141 and 142 is continuously supplied with liquid at supercharge pressure.

The arrangement is such that a force proportional to pump pressure is transmitted from rocker 20 to wobble plate 13 through one-half of element 22 and a force proportional to the supercharge pressure is transmitted from rocker 20 to wobble plate 13 through the other half of element 22. The greater part of those forces are transmitted to wobble plate 13 through the liquid in ports 141 and 142. Element 22 thus functions as a hydraulic thrust bearing through which forces are transmitted from rotatable rocker 20 to non-rotatable wobble plate 13 and it also functions as a valve for connecting one set of hydraulic motors 144 or 146 to the cylinders 10 containing inward moving pistons and for connecting the other set of hold-up motors 144 or 146 to the cylinders 10 containing outward moving pistons.

The front face of rocker 20 and the rear face of the body portion of driving head 21 are arcuate and have the radii thereof struck from the axis of pins 152. Rocker 20 has two curved liners 153 and 154 (Figs. 5, 12 and 13) arranged upon its arcuate front face at opposite sides of shaft 5. Preferably, each of the two liners engages a liner arranged upon the arcuate rear face of head 21 but in order to simplify the drawings the liners on head 21 have been omitted and liners 153 and 154 have been shown as engaging the arcuate rear face of head 21.

As shown in Figs. 12 and 13 liner 153 has an elongated pressure chamber 155 formed in its front face and a drainage groove 156 extending around chamber 155 and spaced outward a short distance therefrom. A hole 157 extends through liner 153 at the center of chamber 155 and a hole 157^a extends through liner 153 at each end of chamber 155. Since liner 154 is identical to liner 153, it has not been shown in detail and a description thereof is deemed unnecessary.

Liner 153 is urged against the arcuate rear face of driving head 21 by a hold-up motor 158 and two hold-up motors 158^a which are arranged in rocker 20 at one side of shaft 5 with motor 158 concentric with the hole 157 in liner 153 and each of the motors 158^a concentric with one of the holes 157^a in liner 153. Likewise, liner 154 is urged against the arcuate rear face of driving head 21 by a hold-up motor 159 and two hold-up motors 159^a which are arranged in rocker 20 at the other side of shaft

5 with motor 159 concentric with the hole 157 in liner 154 and each of the motors 159^a concentric with one of the holes 157^a in liner 154.

Hold-up motors 158, 158^a, 159 and 159^a are identical and, as shown in Fig. 12, each includes a cylinder 160 which is formed in rocker 20, a hollow piston 161 which is fitted in cylinder 160 and has a hole 162 extending through its head end, a sealing member 163 which is arranged between piston 161 and liner 153 or 154, and a spring 164 for urging piston 161 against sealing member 163 and member 163 against liner 153 or 154. The mating surfaces of piston 161 and member 163 are made flat and smooth and the mating surfaces of member 163 and liner 153 or 154 are made spherical and smooth to provide substantially liquid tight joints therebetween.

Sealing member 163 has two recesses 165 and 166 formed in its opposite faces concentric with hole 162 and a hole 157 or 157^a and connected to each other by a hole 167 so that cylinder 160 and recesses 155, 165 and 20 166 are interconnected and any pressure therein will cause liquid to seep from chambers 155 and recesses 165 and 166 and form lubricating films between the mating surfaces of the piston, the sealing member, the liner and the driving head. The arrangement is such that 25 the greater part of a force transmitted from driving head 21 to rocker 20 is transmitted through the liquid in chamber 155, the liquid in recesses 165 and 166 and the liquid in cylinder 160 to rocker 20 and only a small part of the force is transmitted through the films of liquid 30 between the metal parts.

Hold-up motor 158 communicates through a passage 168 with the hole 151 in the piston 149 of hold-up motor 144, as shown in Figs. 5 and 12, so that the pressure prevailing in port 141 will extend therefrom through 35 hole 145, motor 144, hole 151, passage 168, motor 158 and hole 157 into the pressure chamber 155 in liner 153 and from chamber 155 through holes 157^a into motors 158^a so that the force transmitted from driving head 21 to rocker 20 through the liquid in pressure chamber 155 and through motors 158 and 158^a is proportional to the pressure in port 141.

Likewise, hold-up motor 159 communicates through a passage 169 with the hole 151 in the piston or hold-up motor 146, as shown in Fig. 5, so that the pressure prevailing in port 142 will extend therefrom through hole 45 147, motor 146, hole 151, passage 169, motor 159 and hole 157 into the pressure chamber 155 in liner 154 and from chamber 155 through holes 157^a into motors 159^a so that the force transmitted from driving head 21 to 50 rocker 20 through the liquid in pressure chamber 155 and through motors 159 and 159^a is proportional to the pressure in port 142.

The front face of driving head 21 engages a spacer block 175 (Figs. 5 and 20) the front face of which is engaged by a hold-up block 176. Blocks 175 and 176 are rigidly secured to each other and to head 21 and substantially form parts of head 21 but are made separately therefrom for convenience in manufacture. As shown in Figs. 5 and 23, block 176 has a plurality of hold-up motors 177 (three being shown) arranged therein at one side of shaft 5 and an equal number of hold-up motors 178 arranged therein at the other side of shaft 5. Hold-up motors 177 and 178 react against an annular abutment 179 which is carried by end head 2 and extends around shaft 5.

Hold-up motors 177 and 178 are alike and, as shown in Fig. 5, each includes a cylinder 180 which is formed in block 176, a hollow piston 181 which is fitted in cylinder 180 and has a spherical outer end, an annular sealing member or shoe 182 which is arranged between abutment 179 and the spherical outer end of piston 181, and a spring 183 which is arranged within piston 181 and urges piston 181 against shoe 182 and shoe 182 against abutment 179. The mating surfaces of abutment 179 and shoe 182 are made flat and smooth and the mating

surfaces of shoe 182 and the head end of piston 181 are made spherical and smooth to provide therebetween joints which are substantially liquid tight but liquid will seep between piston 181 and shoe 182 and between shoe 182 and abutment 179 and form lubricating films therebetween.

When cylinder 180 is supplied with liquid under pressure, piston 181 will urge shoe 182 against abutment 179 and a hold-up force will be transmitted from abutment 179 through the liquid in cylinder 180 and through spacer block 175 to driving head 21. Shoe 182 has been mentioned as being annular but it may be of any shape providing that it has an opening extending therethrough of such size that a large part of the hold-up force is transmitted through the liquid in the opening in the shoe to thereby limit the force which is transmitted through the films of liquid between abutment 179 and shoe 182 and between shoe 182 and piston 181. When the pump is driven, driving head 21 and blocks 175 and 176 will rotate, shoes 182 will slide around upon abutment 179, and the liquid in the openings through shoes 182 will act as liquid bearings between abutment 179 and shoes 182.

In order that the several hold-up motors on each side of shaft 5 may be connected to each other, each piston 181 has an annular groove 184 formed in its outer peripheral surface and connected to its interior by suitable holes formed in its side wall. As shown in Fig. 23, the grooves 184 in the pistons 181 of hold-up motors 177 are connected to each other by a passage 185 formed in hold-up block 176, and the grooves 184 in the pistons 181 of hold-up motors 178 are connected to each other by a passage 186 formed in hold-up block 176. As shown in Fig. 5, one of the hold-up motors 177 is connected to the pressure chamber 155 in liner 153 by a passage 187 formed in spacer block 175 and in the body portion of driving head 21, and one of the hold-up motors 178 is connected to the pressure chamber 155 in liner 154 by a passage 188 formed in spacer block 175 and in the body portion of driving head 21.

The arrangement is such that pressure will extend from the pressure chamber 155 in liner 153 through passage 187 into the cylinder 180 of one motor 177 and from that cylinder through grooves 184 and passage 185 into the cylinders 180 of the other two motors 177. Likewise, pressure will extend from the pressure chamber 155 in liner 154 through passage 188 into cylinder 180 of one motor 178 and from that cylinder through grooves 184 and passage 186 into the cylinders 180 of the other two motors 178. Since the pressure in the chamber 155 in liner 153 is the same as the pressure in the port 141 in element 22 and since the pressure in the chamber 155 in liner 154 is the same as the pressure in the port 142 in element 22 as previously explained, the pressure in motors 177 will be the same as the pressure in port 141 and the pressure in motors 178 will be the same as the pressure in port 142.

Counterbalance and stroke change mechanism

When the pump is at zero stroke, the rear face of rocker 20 is at right angles to the axis of shaft 5 and an equal amount of the weight of rocker 20 is at opposite sides of the axis of shaft 5 so that the centrifugal forces set up in rocker 20 by rotation thereof are balanced. But when rocker 20 is swung about the axis of pins 152 from its zero stroke position to effect reciprocation of pistons 11, more of the weight of rocker 20 is on one side of the axis of shaft 5 than on the other side thereof so that unbalanced centrifugal forces are set up in rocker 20 by rotation thereof.

In order to counterbalance the centrifugal forces in rocker 20, the pump is provided with a counterbalance 200 which, as shown in Figs. 1, 3 and 5, extends around driving head 21 and has two arms 200a fixed to opposite sides thereof and journaled upon pins 152. When rocker

20 is swung upon pins 152 in one direction to change pump displacement, counterbalance 200 is swung upon pins 152 in the opposite direction, as will presently be explained, and the mass of counterbalance 200 is so proportioned and located that the unbalanced centrifugal forces in rocker 20 are neutralized by the unbalanced centrifugal forces in counterbalance 200.

When rocker 20 and counterbalance 200 are swung in opposite directions from their neutral position and are rotated, the unbalanced centrifugal forces in each tends to swing it farther from its neutral position. In order to relieve the stroke changing mechanism from at least a part of each of the forces tending to move rocker 20 and counterbalance 200 farther from their neutral positions, the pump is provided with two tensioning devices 201 which oppose movement of counterbalance 200 away from its neutral position.

As shown in Figs. 17 and 18, each device 201 includes a housing 202 which engages the flange 21a of driving head 21 and extends around an opening 203 formed in flange 21a. Housing 202 has two spring chambers 204 and 205 formed therein and a pair of lugs 206 formed thereon and extending through opening 203. Lugs 206 are connected by a pin 207 to the central portion of the front end of a lever 208 the other end of which is bifurcated and has a roller 209 arranged therein upon a pin 210. Roller 209 is fitted in an annular bushing 211 which is fixed in and extends through the radial flange of counterbalance 200.

Each of spring chambers 204 and 205 has a spring 212 arranged therein between two annular spring retainers 213 and 214. Retainer 213 normally engages the front end of the spring chamber and it is engaged by a block 215 which is slidable in the front end of the spring chamber. Retainer 214 normally engages the rear end of the spring chamber and it is engaged by a block 216 which is slidable in the rear end of the spring chamber. Block 215 is connected by a bolt 217 to a clevis 218 which engages block 216 and extends through the opening 203 in driving head 21. The two clevises 218 are connected by two pins 219 to the front end of lever 208 at opposite sides of pin 207.

The arrangement is such that, when counterbalance 200 is swung in one direction or the other about the axis of pins 152, rollers 209 will cause levers 208 to pivot upon pins 207. Each lever 208 will compress the spring 212 in one spring chamber against the front end of that chamber and will compress the spring 212 in the other spring chamber against the rear end of that chamber and the combined forces exerted by the springs 212 will tend to return counterbalance 200 to its central position and will thereby oppose centrifugal forces which tend to move counterbalance 200 and rocker 20 farther from their neutral positions.

The present invention is especially applicable to very large pumps in which the centrifugal forces set up in the rocker and in the counterbalance are very high. When the pump is running at full stroke, the masses of the rocker and the counterbalance are at their maximum radii and the centrifugal forces are so great that a stroke changing device of ordinary size could not return the rocker and the counterbalance to their zero stroke positions. Even if an over-size stroke changing device were provided, it would be impossible to reduce the pump stroke if the stroke changing device should fail to operate. It therefore is highly desirable to make the tensioning devices 201 strong enough to overcome the centrifugal force moments of the rocker and the counterbalance so that the stroke changing mechanism has to help the centrifugal forces to compress springs 212 during an increase in pump stroke. Then should the stroke changing mechanism fail to operate, such as by failure of the supply of power thereto, the energy stored in springs 212 would return the rocker and the counterbalance to their zero stroke positions.

Rocker 20 is adapted to be swung in either direction upon the axis of pins 152 by motion transmitted thereto through two convex racks 225 (Figs. 5 and 16) which are fixed to opposite sides thereof, and counterbalance 200 is adapted to be swung in the opposite direction about the axis of pins 152 by motion transmitted thereto through two concave racks 226 (Figs. 5, 15 and 16) which are fixed to opposite sides thereof in alignment with the two racks 225 respectively.

The two racks 225 and 226 on each side of shaft 5 mesh with a pinion 227 and with a pinion 228. The two pinions 227 are fixed upon opposite ends of a shaft 229 which is journaled in driving head 21 and has a pinion 230 fixed to or formed thereon. The two pinions 228 are fixed upon opposite ends of a shaft 231 which is journaled in driving head 21 and has a pinion 232 fixed to or formed thereon. Pinion 232 meshes with a pinion 233 arranged upon a shaft 234 carried by driving head 21.

Pinion 230 meshes with a rack 235 shown in Fig. 19 as being formed integral with a piston rod 236 which is slideable in driving head 21 and in hold-up block 176. Piston rod 236 has a piston 237 fixed thereon and fitted in a cylinder 238 which is formed in spacer block 175 and forms with piston 237 and rod 236 a hydraulic motor for rotating shaft 229. Pinion 233 meshes with a rack 239 shown in Fig. 19 as being formed integral with a piston rod 240 which is slideable in driving head 21 and in hold-up block 176. Piston rod 240 has a piston 241 fixed thereon and fitted in a cylinder 242 which is formed in spacer block 175 and forms with piston 241 and rod 240 a hydraulic motor for rotating shaft 231.

The arrangement is such that, when liquid is supplied to the rear ends of cylinders 238 and 242 and causes pistons 237 and 241 to move forward, shafts 229 and 231 will be rotated in a direction to cause pinions 227 and 228 to move racks 225 and rocker 20 in one direction and to move racks 226 and counterbalance 200 in the opposite direction and, when liquid is supplied to the front ends of cylinders 238 and 242 and causes pistons 237 and 241 to move rearward, shafts 229 and 231 will be rotated in the opposite direction and thereby reverse the movements of rocker 20 and counterbalance 200.

Liquid for operating motors 236—238 and 240—242 is supplied thereto under the control of a pilot valve 250 which, as shown in Fig. 20, is arranged within spacer block 175. Liquid is supplied to pilot valve 250 under the control of a selector valve 251 which, as shown in Fig. 23, is arranged within hold-up block 176.

As shown in Fig. 24, pilot valve 250 is provided with two end heads or pistons 252 and 253 and with two intermediate heads or pistons 254—255 and is fitted in the bore of a sleeve 256 which is arranged within spacer block 175. Sleeve 256 has two annular grooves or ports 257 and 258 formed in the wall of its bore and normally covered, respectively, by pistons 254 and 255 which have been shown as being of the same width as the ports so that the ports are partially opened in response to a slight movement of valve 250.

Port 257 communicates with the rear or right ends of cylinders 238 and 242 through a channel 259, and port 258 communicates with the front or left ends of cylinders 238 and 242 through a channel 260. Sleeve 256 has formed in the wall thereof between ports 257 and 258 a plurality of holes 261 which communicate with a channel 262 through which motive liquid is continuously supplied to the space between pistons 254 and 255 as will presently be explained. The space between pistons 252 and 254 communicates with an exhaust channel 263 through holes 264 formed in the wall of sleeve 256, and the space between pistons 253 and 255 communicates with an exhaust channel 265 through holes 266 formed in the wall of sleeve 256.

The arrangement is such that, when pilot valve 250 is moved a very short distance downward in respect to Fig. 24, liquid can flow from channel 262 through sleeve 256 and channel 260 to the front or left ends of cylinders 238

and 242 and moves pistons 237 and 241 rearward or toward the right and, when pilot valve 250 is moved a very short distance upward in respect to Fig. 24, liquid can flow from channel 262 through sleeve 256 and channel 259 to the rear or right ends of cylinders 238 and 242 and move pistons 237 and 241 forward or toward the left.

As shown in Figs. 23 and 24, selector valve 251 is fitted in a sleeve 270 which has two annular grooves or ports 271 and 272 formed in the wall of the bore thereof and which is fitted in a bore 273 formed in spacer block 176. Port 271 communicates through suitable holes in the wall of sleeve 270 with an annular groove 274 which is formed in the wall of bore 273 and is connected by a channel 275 to one of the hold-up motors 177. Port 272 communicates through suitable holes in the wall of sleeve 270 with an annular groove 276 which is formed in the wall of bore 273 and is connected by a channel 277 to one of the hold-up motors 178.

Valve 251 has a cannelure 278 formed therein intermediate its ends and two ducts 279 and 280 extending axially into it from its opposite ends to points short of cannelure 278 and then extending radially outward into communication with ports 271 and 272 respectively. Cannelure 278 communicates with channel 262 through suitable holes formed in the wall of sleeve 270. Movement of valve 251 in either direction is limited by one or the other of two stops 281 and 282 which close opposite ends of sleeve 270.

It has previously been explained that pump pressure prevails in one set of hold-up motors 177 and 178 and that supercharge pressure prevails in the other set of hold-up motors 177 and 178. When pump pressure prevails in motors 178, liquid will flow therefrom through channel 277, groove 276, port 272 and duct 280 into the end of sleeve 270 which is the upper end in respect to Fig. 24 and the liquid will move valve 251 downward in respect to Fig. 24 against stop 281 to close port 272 and to open port 271. Then liquid will flow from motors 177 through channel 275, groove 274, port 271, cannelure 278, channel 262 and holes 261 into the space between pistons 254 and 255 of pilot valve 250. When pump pressure prevails in motors 177, liquid will flow therefrom through channel 275, groove 274, port 271 and duct 279 into the end of sleeve 270 which is the lower end in respect to Fig. 24 and the liquid will move valve 251 upward in respect to Fig. 24 against stop 282 to close port 271 and to open port 272. Then liquid will flow from motors 178 through channel 277, groove 276, port 272, cannelure 278, channel 262 and holes 261 into the space between the pistons 254 and 255 of pilot valve 250. Pilot valve 250 is thus always supplied with liquid at supercharge pressure and, consequently, stroke change motors 236—238 and 240—242 are always operated by liquid at supercharge pressure.

Pilot valve 250 may be operated in any suitable manner. For the purpose of illustration, it has been shown in Fig. 20 as having its upper end in respect to the drawing in engagement with a follow-up lever 290 intermediate the ends thereof, valve 250 being held against lever 290 by centrifugal force when the pump is operating. The rear end of lever 290 is pivoted to one end of a crank 291 (Figs. 16, 20 and 21) having the other end thereof fixed upon one end of a shaft 292 which is journaled in a bearing 293 carried by driving head 21. A crank 294 has one of its ends fixed to the other end of shaft 292 and its other end provided with a roller 295 to engage an arcuate cam 296 which is fixed to rack 226. Roller 295 is held in contact with cam 296 by a spring 297 shown as being arranged between crank 291 and the annular shell 21^b of driving head 21.

The front end of lever 290 is urged by a spring 298 against the radially outward end of a rod 299 which is slideable in block 176 and has its inner end in engagement with the substantially horizontal arm 300 (Figs. 20 and 23) of a lever which has a bifurcated substan-

tially vertical arm 301 and is pivoted by a pin 302 to a support 303 carried by block 176. Arm 301 straddles shaft 5 and has its radially inward ends connected by bolts 304 to a ring 305 which encircles shaft 5 and is movable longitudinally thereof to effect variations in pump displacement. Bolts 304 connect the ends of lever arm 301 to ring 305 in such a manner that the ends of arm 301 are positively moved in synchronism with ring 305 and lever 300—301 can pivot upon pin 302.

The arrangement is such that, when ring 305 is moved rearward along shaft 5, lever 300—301 will pivot upon pin 302 and will cause rod 299 to raise the front end of lever 290 which will permit pilot valve 250 to be moved radially outward by centrifugal force. Moving valve 250 outward will cause counterbalance 209 and cam 296 to be swung downward in respect to Figs. 1 and 16 and cam 296 will permit spring 297 to move the rear end of lever 290 radially inward as fast as the front end of lever 290 is moved outward so that adjustment of the pump will cease as soon as movement of ring 305 ceases. Movement of ring 305 forward along shaft 5 will cause the parts to move in substantially the above described manner but in the opposite directions.

The actual mechanism for moving ring 305 along shaft 5 is quite complicated and does not, per se, form a part of the present invention. Therefore, the pump has been shown in Figs. 5, 20 and 22 as being provided with a simpler mechanism. As shown, ring 305 engages the rear end of a sleeve 310 which is slideable in two bushings 311 and 312 closely fitted in end head 2. Rotation of sleeve 310 and bushing 311 is prevented in any suitable manner such as by means of a key 313 (Fig. 20) which prevents sleeve 310 from rotating in bushing 311 and a pin 314 (Fig. 5) which prevents bushing 311 from rotating in end head 2. Sleeve 310 has journaled thereon a worm wheel 315 having teeth on only a part of its outer periphery and in mesh with a worm 316 which is fixed upon a shaft 317 journaled in bearings 318 carried by end head 2. Worm wheel 315 has fixed therein a pin 319 which extends into a helical slot 320 formed in sleeve 310.

The arrangement is such that, when worm 316 is rotated in one direction or the other, worm wheel 315 will be rotated in one direction or the other and pin 319 will move along slot 320 and, since slot 320 is formed diagonally in sleeve 310, pin 319 will move sleeve 310 forward or rearward depending upon the direction of rotation of worm 316.

FIGS. 26-32

The pump shown in these figures differs primarily from the pump shown in Figs. 1-25 in that the hydraulic hold-up element which functions both as a valve and as a hydraulic thrust bearing is arranged between the rotating structure and the end head of the pump casing instead of being arranged between the rotating structure and the wobble plate, and liquid is supplied to that element from the pumping cylinders through channels which are independent of the passages through the pumping pistons.

More specifically, hold-up element 22 (Figs. 1, 5 and 11) is omitted from between wobble plate 13 and rocker 20, a similar element is substituted for hold-up motors 177 and 178 (Figs. 5 and 23), and abutment 179 (Figs. 5 and 20) is replaced by a valve seat to which liquid is directed from cylinders 10 through channels which are outside the rotating structure. These differences necessitate certain changes in the structure but otherwise the two pumps are the same. Therefore, insofar as the parts are shown in Figs. 26-32, like parts have been indicated by like reference numerals and corresponding parts have been indicated by corresponding reference numerals with an exponent added to the reference numerals applied to Figs. 26-32.

Since element 22 is omitted, the piston reciprocating mechanism includes a wobble plate 13^x which is the same as wobble plate 13 except that passages 134 (Figs. 8 and

10) are omitted therefrom, a rocker 20^x which is the same as rocker 20 except that recess 23 and passages 168 and 169 (Figs. 5 and 24) are omitted therefrom, and a plurality of piston shoes 24^x which are the same as but somewhat larger than shoes 24 because all of the pumping forces must be transmitted through the shoes. The piston reciprocating mechanism is otherwise the same as the piston reciprocating mechanism of the pump shown in Figs. 1-25.

The channels for conducting liquid from cylinders 10 to the valve seat for the hold-up element may be arranged in any suitable manner. As shown, the pump casing includes a substantially annular body portion 1^a having inwardly extending annular flanges 1^b and 1^c formed upon its opposite ends, a front head 2^a which is rigidly attached to flange 1^b and a rear end portion or rear head 1^d which is rigidly attached to flange 1^c and has formed therein an axial bore 25 having tightly fitted therein a cylinder block 3^a in which cylinders 10 are arranged.

The portion of end head 1^d in contact with flange 1^c has a plurality of recesses 330 formed therein with each recess 330 in the same radial plane as one of the cylinders 10. The portion of end head 2^a in contact with flange 1^b has a recess 331 formed therein in axial alignment with each recess 330 to which it is connected by a tube 332 which has its opposite ends sealed in flanges 1^b and 1^c respectively. Each recess 330 communicates with the cylinder 10 in the same radial plane through a passage 333 which is formed in rear head 1^d and in cylinder block 3^a. Except for recesses 330 and passages 333 and for the fact that rear head 1^d is made separate from and is attached to the body of the casing, cylinder block 3^a and rear head 1^d are the same, respectively, as the cylinder block 3 and the rear end portion of the casing 1 of the pump shown in Figs. 1-25.

End head 2^a has an annular recess 334 formed therein concentric with shaft 5 to receive an annular valve seat 335 which is tightly fitted therein and restrained from rotation. Valve seat 335 has a plurality of passages 336 formed therein in a circular row with each passage 336 in the same radial plane as one of the cylinders 10. Each passage 336 extends axially forward from the rear face of valve seat 335 and then extends radially outward into communication with a passage 337 which is formed in front head 2^a and is connected to the recess 331 in the same radial plane by a tube 338 which has its ends sealed in end head 2^a.

The arrangement is such that each passage 336 communicates with the cylinder 10 in the same radial plane through a passage 337, a tube 338, a recess 331, a tube 332, a recess 330 and a passage 333 so that liquid can flow therebetween and the pressure in each passage 336 will be the same as the pressure in the cylinder 10 in the same radial plane.

Valve seat 335 is engaged by a hold-up element 339 which performs the same functions that are performed by the hold-up element 22 in the pump shown in Figs. 1-25. That is, it transmits forces between the rotating structure and a part of the non-rotating structure, it supplies liquid at pump pressure to the hold-up motors in that half of the rotating structure which causes the pistons 11 to be advanced on working strokes, it supplies the hold-up motors in the other half of the rotating structure with liquid at the pressure prevailing at the intake of the pump, and it supplies liquid at pump pressure to one and liquid at the intake pressure to the other of the two ports 274 and 276 which extend around selector valve 251 (Figs. 23 and 24). It also combines the functions of element 22 and hold-up motors 177 and 178 (Figs. 5 and 24).

Hold-up element 339 is arranged within an annular flange 340 formed upon a block 176^a which is similar to block 176 (Figs. 5 and 23) and has selector valve 251 arranged therein and has the piston rods 236 and 240 of the stroke changing motors mounted therein. Block 176^a is fixed for rotation with shaft 5 and has element 339

fixed for rotation therewith as by means of a key 341. Flange 340 restrains element 339 from radial movement but permits it to have a limited axial movement and to adjust itself to valve seat 335.

Preferably, suitable wear plates are arranged between valve seat 335 and element 339 but in order to simplify the drawings such wear plates have been omitted therefrom, element 339 has been shown as having a narrow annular boss 342 (Fig. 27) formed upon its front end to contact valve seat 335, and two arcuate grooves or ports 343 and 344 are formed in boss 342 upon the same radius as the outer or rear ends of the passages 336 in valve seat 335. The arrangement is such that the several passages 336 will register successively with each of said ports and each passage 336 will register with the two ports alternately during rotation of element 339.

It has previously been explained that, when rocker 29 Fig. 1 is swung about the axis of pins 152 (Figs. 3 and 5) away from its neutral position, the pistons 11 in axial alignment with one-half of rocker 29 will be progressively advanced on working strokes and the pistons in axial alignment with the other half of rocker 29 will be progressively retracted. The center line 345 (Fig. 27) of element 339 is at right angles to the axis of pins 152, and ports 343 and 344 are equally spaced upon opposite sides of that centerline. Since each passage 336 is connected to the cylinder 10 in the same radial plane and registers with ports 343 and 344 alternately during rotation of element 339, one of ports 343 and 344 is always supplied with liquid at pump pressure and the other one of ports 343 and 344 is always supplied with liquid at the pressure prevailing in the cylinders containing retracting pistons which in the present case is the supercharge pressure.

Hold-up element 339 includes as many hold-up motors as may be necessary to transmit the piston reactions from the rotating structure to the pump casing. As shown in Fig. 27, element 339 is provided behind port 343 with a hold-up motor 346 and two hold-up motors 346^a, each of which communicates with port 343 through a hole 347, and it is provided behind port 344 with a hold-up motor 348 and two hold-up motors 348^a each of which communicates with port 344 through a hole 349.

Hold-up motors 346, 346^a, 348 and 348^a are alike except that the piston of each of motors 346 and 348 has a hole extending through its end wall while the pistons of motors 346^a and 348^a do not. As shown in Fig. 32, hold-up motor 346 includes a cylinder 350 which is formed in element 339, a hollow piston 351 which is fitted in cylinder 350 and has a hole 352 extending through its end wall, and a spring 353 which is arranged within piston 351 and urges piston 351 against block 176^a and element 339 against valve seat 335. Motor 348 is identical to motor 346. As shown in Fig. 31, each hold-up motor 348^a includes a cylinder 350 which is formed in element 339, a hollow piston 351^a which is fitted in cylinder 350 and is the same as piston 351 except that it has no hole 352 therein, and a spring 353 which urges piston 351^a against block 176^a and element 339 against valve seat 335. Motors 346^a are identical to motors 348^a.

As shown in Fig. 26^a, the hole 352 in hold-up motor 346 communicates with the passage 187 in spacer block 175 through a passage 354 formed in block 176^a, and the hole 352 in hold-up motor 348 communicates with the passage 188 in spacer block 175 through a passage 355 formed in block 176^a. Passages 354 and 355 are also connected, respectively, to two passages 356 and 357 (Fig. 29) which are formed in block 176^a and communicate, respectively, with the two ports 274 and 276 which surround the sleeve 270 of selector valve 251. As previously explained and as shown in Fig. 5, pas-

sage 187 communicates with the port 155 in liner 153 and passage 188 communicates with the port 155 in liner 154.

The arrangement is such that hold-up motors 346 and 346^a will be energized by liquid at the pressure prevailing in port 343 and that pressure will extend through passages 354 and 356 (Figs. 26^a and 29) to the port 274 of selector valve 251 and it will extend through passages 354 and 187 to the port 155 in liner 153 (Figs. 5 and 24) and from that port into hold-up motors 158 and 158^a. Likewise, hold-up motors 348 and 348^a will be energized by liquid at the pressure prevailing in port 344 and that pressure will extend through passages 355 and 357 (Figs. 26^a and 29) to the port 276 of selector valve 251 and it will extend through passages 355 and 188 to the port 155 in liner 154 (Figs. 5 and 24) and from that port into hold-up motors 159 and 159^a. Therefore, hold-up devices between the rocker and the driving head and the hold-up devices between block 176^a and valve seat 335 in that half of the rotating structure which causes pistons 10 to be advanced on working strokes are energized by liquid at pump pressure and the hold-up devices between the rocker and the driving head and the hold-up devices between block 176^a and valve seat 335 in that half of the rotating structure which causes or permits pistons 10 to be retracted are energized by liquid at the pressure prevailing in cylinders containing retracting pistons which in the present instance is the supercharge pressure.

The pump is otherwise the same and functions in the same manner as the pump shown in Figs. 1-25. Other modifications may be made without departing from the scope of the invention which is hereby claimed as follows:

35 1. In a pump having a housing, a plurality of stationary and substantially parallel pumping cylinders arranged in a circle within said housing, and a piston fitted in each of said cylinders, the combination of a drive shaft journaled in said housing with its axis passing through the center of said cylinder circle, a hollow spherical bearing extending around said shaft in front of said cylinders and supported from said housing, a wobble plate pivotally supported upon said bearing and having said pistons connected thereto, a universal joint connecting said wobble plate to said housing to prevent it from rotating while permitting it to wobble upon said bearing, a driving head fixed upon said shaft and restrained from axial movement, a thrust member extending around said shaft in engagement with said driving head and connected thereto to rotate therewith, said wobble plate being inclined to the shaft axis when the pump is functioning, and means arranged between said wobble plate and said thrust member for transmitting pumping forces from said thrust member to said pistons and said wobble plate to thereby cause said pistons to be reciprocated and said wobble plate to wobble upon said bearing in response to rotation of said shaft.

2. In a pump having a housing, a plurality of stationary and substantially parallel pumping cylinders arranged in a circle within said housing, and a piston fitted in each of said cylinders, the combination of a drive shaft journaled in said housing with its axis passing through the center of said cylinder circle, a hollow spherical bearing extending around said shaft in front of said cylinders and supported from said housing, a wobble plate pivotally supported upon said bearing and having said pistons connected thereto, a universal joint connecting said wobble plate to said housing to prevent it from rotating while permitting it to wobble upon said bearing, a driving head fixed upon said shaft and restrained from axial movement, a thrust member extending around said shaft in engagement with said driving head and connected thereto to rotate therewith, said thrust member having a flat rear face which is inclined to the shaft axis when the pump is functioning, and hydraulic thrust bearings ar-

ranged between said wobble plate and the rear face of said thrust member for transmitting pumping forces from said thrust member to said pistons and said wobble plate to thereby cause said pistons to be reciprocated and said wobble plate to wobble upon said bearing in response to rotation of said shaft.

3. In a pump having a housing, a plurality of stationary and substantially parallel pumping cylinders arranged in a circle within said housing, and a piston fitted in each of said cylinders, the combination of a drive shaft journaled in said housing with its axis passing through the center of said cylinder circle, a hollow spherical bearing arranged in front of said cylinders and concentric with said shaft, a wobble plate pivotally supported upon said bearing and having said pistons connected thereto, a universal joint connecting said wobble plate to said housing to prevent it from rotating while permitting it to wobble upon said bearing, a driving head fixed upon said shaft and restrained from axial movement, a thrust member extending around said shaft, in engagement with said driving head and connected thereto to rotate therewith, said thrust member having a flat rear face and being pivoted upon an axis which is normal to said shaft and extends through the center of said spherical bearing, means arranged between said wobble plate and said thrust member for transmitting pumping forces from said thrust member to said pistons and for maintaining said wobble plate parallel to the rear face of said thrust member, and means connected to said thrust member for swinging the same about said axis from a neutral position in which its rear face is normal to said shaft to a selected position in which its rear face is inclined to said shaft and rotation of said thrust member causes said pistons to be reciprocated and said wobble plate to wobble upon said bearing.

4. In a pump having a housing, a plurality of stationary and substantially parallel pumping cylinders arranged in a circle within said housing, and a piston fitted in each of said cylinders, the combination of a drive shaft journaled in said housing with its axis passing through the center of said cylinder circle, a hollow spherical bearing arranged in front of said cylinders and concentric with said shaft, a wobble plate pivotally supported upon said bearing and having said pistons connected thereto, a universal joint connecting said wobble plate to said housing to prevent it from rotating while permitting it to wobble upon said bearing, a thrust member extending around said shaft in front of said wobble plate and rotatable with said shaft, said thrust member having a flat rear face and being pivoted upon an axis which is normal to said shaft and extends through the center of said spherical bearing, means engaging the rear face of said thrust member and rotatable with said shaft for restraining said thrust member from axial movement, hydraulic thrust bearings carried by said wobble plate and engaging the flat rear face of said thrust member for transmitting pumping forces from said thrust member to said pistons and said wobble plate as said thrust member rotates, and means connected to said thrust member for swinging the same about said axis from a neutral position in which its rear face is normal to said shaft to a selected position in which its rear face is inclined to said shaft and rotation of said thrust member causes said pistons to be reciprocated and said wobble plate to wobble upon said bearing.

5. In a pump, a combination as set forth in claim 3 and including a counterbalance pivotally connected to said thrust member upon the same axis upon which said thrust member is pivoted, and means connected to said counterbalance and to said thrust member and responsive to said thrust member being swung through a given angle in one direction for simultaneously swinging said counterbalance through a proportionate in the opposite direction.

6. In a pump, a combination as set forth in claim 4 and including a counterbalance pivotally connected to

said thrust member upon the same axis upon which said thrust member is pivoted, and means connected to said counterbalance and to said thrust member and responsive to said thrust member being swung through a given angle in one direction for simultaneously swinging said counterbalance through a proportionate angle in the opposite direction.

7. In a pump having a housing, a plurality of stationary and substantially parallel pumping cylinders arranged in a circle within said housing, and a piston fitted in each of said cylinders, the combination of a drive shaft journaled in said housing with its axis passing through the center of said cylinder circle, means operatively associated with said pistons for effecting reciprocation thereof including a thrust member rotatable with said shaft and swingable about an axis normal to said shaft from a neutral position in which no reciprocation of said pistons occurs to selected positions in which said thrust member in response to rotation thereof effects reciprocation of said pistons, means engaging said thrust member for restraining it from axial movement, means connected to said thrust member for swinging it from one position to another, a counterbalance rotatable with said shaft and swingable about the same axis about which said thrust member is swingable, and means connecting said counterbalance to said thrust member and responsive to said thrust member being swung through a given angle in one direction for simultaneously swinging said counterbalance through a proportionate angle in the opposite direction.

8. In a pump having a housing, a plurality of stationary and substantially parallel pumping cylinders arranged in a circle within said housing, and a piston fitted in each of said cylinders, the combination of a drive shaft journaled in said housing with its axis passing through the center of said cylinder circle, means operatively associated with said pistons for effecting reciprocation thereof including a thrust member rotatable with said shaft and swingable about an axis normal to said shaft from a neutral position in which no reciprocation of said pistons occurs to selected positions in which said thrust member in response to rotation thereof effects reciprocation of said pistons, means engaging said thrust member for restraining it from axial movement, means connected to said thrust member for swinging it from one position to another, the weight of said thrust member being so distributed that rotation thereof when in its neutral position causes substantially no unbalanced centrifugal forces to be created therein but rotation of said thrust member when in a position to effect reciprocation of said pistons causes unbalanced centrifugal forces to be created therein, a counterbalance rotatable with said shaft and swingable about said axis, the weight of said counterbalance being so distributed that rotation thereof when in its neutral position causes substantially no unbalanced centrifugal forces to be created therein but rotation of said counterbalance when not in its neutral position causes unbalanced centrifugal forces to be created therein, and means connecting said counterbalance to said thrust member and responsive to said thrust member being swung through a given angle in one direction for simultaneously swinging said counterbalance in the opposite direction through such an angle that the unbalanced centrifugal forces in said counterbalance are opposite and approximately equal to the unbalanced centrifugal forces in said thrust member.

9. In a pump having a housing, a plurality of stationary and substantially parallel pumping cylinders arranged in a circle within said housing, a piston fitted in each of said cylinders, a drive shaft journaled in said housing with its axis passing through the center of said cylinder circle, and means for effecting reciprocation of said pistons including a thrust member rotatable with said shaft and swingable about an axis normal to said shaft from a neutral position in which no reciprocation of said pistons occurs to selected positions in which said thrust member in response to rotation thereof effects reciprocation of

said pistons, the weight of said thrust member being so distributed that rotation thereof when in its neutral position causes substantially no unbalanced centrifugal forces to be created therein but rotation of said thrust member when in a position to effect reciprocation of said pistons causes unbalanced centrifugal forces to be created therein, the combination with said thrust member of a counterbalance member rotatable with said shaft and swingable about said axis, the weight of said counterbalance being so distributed that rotation thereof when in its neutral position causes substantially no unbalanced centrifugal forces to be created therein but rotation of said counterbalance when not in its neutral position causes unbalanced centrifugal forces to be created therein, power means connected to said members for swinging said thrust member through a given angle in one direction and simultaneously swinging said counterbalance member in the opposite direction through such an angle that the unbalanced centrifugal forces in said counterbalance member are opposite and approximately equal to the unbalanced centrifugal forces in said thrust member, and tensioning means connected to one of said members for resisting movements of said thrust member and said counterbalance member away from their neutral positions by centrifugal forces and for urging the same toward their neutral positions.

10. The combination set forth in claim 9 in which said pump has a head fixed to said shaft to rotate therewith, said tensioning means includes caged spring means supported by said head, and said spring means is powerful enough to return said thrust member and said counterbalance member to their neutral positions without help from said power means and is constructed to stop the same in their neutral positions.

11. In a pump having a housing, a plurality of stationary and substantially parallel pumping cylinders arranged in a circle within said housing, and a piston fitted in each of said cylinders, the combination of a drive shaft journaled in said housing with its axis passing through the center of said cylinder circle, a bearing concentric with said shaft, a non-rotatable wobble plate pivoted upon said bearing and connected to said pistons, a driving head fixed for rotation with said shaft and restrained from axial movement, a thrust member encircling said shaft between said head and said wobble plate, thrust bearing means arranged between said thrust member and said plate, two pins arranged at opposite sides of said shaft upon an axis normal to said shaft and connecting said thrust member to said head to cause said thrust member to rotate with said head and to permit it to be swung about said axis relatively to said head, means connected to said thrust member for swinging it upon said pins from one position to another position relatively to said head, a convex cylindrical bearing surface arranged upon said thrust member upon a radius struck from said axis, and a complementary concave cylindrical bearing surface arranged upon said head in contact with said convex surface to transmit pumping forces from said head to said thrust member while permitting said thrust member to be swung from one to another position relatively to said head.

12. In a pump having a housing, a plurality of stationary and substantially parallel pumping cylinders arranged in a circle within said housing, and a piston fitted in each of said cylinders, the combination of a drive shaft journaled in said housing with its axis passing through the center of said cylinder circle, a bearing concentric with said shaft, a non-rotatable wobble plate pivoted upon said bearing and connected to said pistons, a driving head fixed for rotation with said shaft and restrained from axial movement, a thrust member encircling said shaft between said head and said wobble plate, thrust bearing means arranged between said thrust member and said plate, two pins arranged at opposite sides of said shaft upon an axis normal to said shaft and connecting said thrust member to said head to cause

said thrust member to rotate with said head and to permit it to be swung about said axis relatively to said head, means connected to said thrust member for swinging it upon said pins from one position to another position relatively to said head, a concave face and a convex face arranged upon said head and said thrust member respectively, the radii of said faces being struck from said axis, and hydraulic thrust bearings arranged between and in contact with said faces for transmitting pumping forces from said head to said thrust member while permitting said thrust member to be swung from one to another position relatively to said head.

13. In a pump having a housing, pumping mechanism arranged within said housing and including a drive shaft journaled in said housing, a thrust member rotatable with said shaft and swingable about an axis normal to said shaft between a neutral position and selected operative positions, and a counterbalance rotatable with said shaft and swingable about said axis, the combination with said thrust member and said counterbalance of gearing connected thereto, hydraulic motor means rotatable with said shaft and connected to said gearing to cause the same to swing said thrust member and said counterbalance in opposite directions simultaneously in response to said motor means being energized, means for supplying motive liquid to said motor means to energize the same including a pilot valve rotatable with said shaft for controlling the flow of liquid to and from said motor means and so constructed that when open it will direct liquid to said motor means but being normally closed to block delivery of liquid to said motor means, a control element operable from outside said housing, and a follow-up mechanism rotatable with said shaft and connected to said pilot valve for opening it in response to said control element being moved and to close said pilot valve in response to said motor means swinging said thrust member through an angular distance proportional to the distance through which said control element was moved.

14. The combination set forth in claim 13 in which said gearing includes at least one arcuate rack fixed to said thrust member, at least one arcuate rack fixed to said counterbalance, and at least one pinion meshing with both of said racks, and which includes a rack operable by said hydraulic motor means for rotating said pinion.

15. In a pump having a housing, a plurality of stationary and substantially parallel pumping cylinders arranged in said housing in a circular row, a piston fitted in each cylinder, a drive shaft journaled in said housing with its axis passing through the center of said circular row, a structure fixed to said shaft to rotate therewith and including a thrust member arranged in front of said pistons in alignment therewith and adjustable to a position inclined to said shaft, a driving head arranged in front of said thrust member, and a first and a second hydraulic thrust bearing arranged between said head and the first half and the second half of said thrust member, and force transmitting means engaging said thrust member and connected to said pistons to cause the pistons in axial alignment with a first half of said thrust member to be progressively advanced and the pistons in axial alignment with the second half of said thrust member to be progressively retracted in response to said thrust member being rotated and inclined to said shaft, the combination of a non-rotatable valve seat carried by said housing and having formed therein in a circular row as many holes as there are cylinders with each hole in substantially the same radial plane as one of said cylinders, fluid channels connecting each of said holes to the cylinder in the same radial plane, a valve rotatable with and carried by said structure in contact with said valve seat and having formed therein upon the same radius as said row of holes a first arcuate port and a second arcuate port which are arranged respectively upon the same sides of said shaft

as said first and said second halves of said thrust member and with which each of said holes registers alternately during rotation of said valve, a first set and a second set of hold-up motors arranged within said valve and communicating with said first port and second port respectively for urging said valve against said valve seat, and fluid channels connecting said first set of hold-up motors to said first thrust bearing and connecting said second set of hold-up motors to said second thrust bearing so that said first set of hold-up motors and said first thrust bearing are supplied with liquid at the pressure prevailing in the cylinders containing advancing pistons and said second set of hold-up motors and said second set of thrust bearings are supplied with liquid at the pressure prevailing in the cylinders containing retracting pistons.

16. A pump comprising a housing, a plurality of stationary and substantially parallel pumping cylinders arranged in said housing in a circular row, a piston fitted in each cylinder, and having a passage extending axially therethrough, a drive shaft journaled in said housing with its axis passing through the center of said circular row, a non-rotatable wobble plate supported by said housing in front of said cylinders and having as many holes as there are cylinders extending into it from its front face and arranged in a circular row with each hole in substantially the same radial plane as one of said cylinders, a connecting rod connecting each of said pistons to said wobble plate and having a passage extending therethrough to provide communication between the passage in that piston and the hole in said wobble plate which is in the same radial plane as said piston, a thrust member extending around said shaft in front of said wobble plate and having a flat rear face which is inclined to the shaft axis when the pump is functioning, hydraulic thrust bearings arranged between said wobble plate and the rear face of said thrust member for transmitting pumping forces from said thrust member to said pistons and said wobble plate, means connected to said thrust member for adjusting it in either direction from a neutral position in which it is normal to said shaft to selected operative positions in which it is inclined to said shaft to thereby cause the pistons in axial alignment with a first half of said thrust member to be progressively advanced and the pistons in axial alignment with the second half of said thrust member to be progressively retracted in response to said thrust member being rotated and inclined to said shaft, a structure fixed to said shaft and engaging said thrust member to restrain it from axial movement, two sets of hold-up motors arranged in said structure and engaging said housing for transmitting forces from said structure to said housing, the first set being arranged upon the same side of said shaft as said first half of said thrust member and the second set being arranged in said structure upon the same side of said shaft as said second half of said thrust member, a valve rotatable with said thrust member in contact with the front face of said wobble plate and having formed therein upon the same radius as said row of holes a first arcuate port and a second arcuate port which are arranged respectively upon the same sides of said shaft as said first and said second halves of said thrust member and with which each of said holes registers alternately during rotation of said valve, and fluid channels connecting said first set of hold-up motors to said first port and connecting said second set of hold-up motors to said second port so that said first set of hold-up motors is supplied with liquid at the pressure prevailing in the cylinders containing advancing pistons and said second set of hold-up motors is supplied with liquid at the pressure prevailing in the cylinders containing retracting pistons.

17. In a pump having a housing, a plurality of stationary and substantially parallel pumping cylinders arranged in said housing in a circular row, a piston fitted in each cylinder, a drive shaft journaled in said housing with its axis passing through the center of said circular

row, a structure fixed to said shaft to rotate therewith and including a thrust member arranged in axial alignment with said pistons and adjustable to a position in which it is inclined to said shaft, and force transmitting means engaging said thrust member and connected to said pistons to cause the pistons in axial alignment with a first half of said thrust member to be progressively advanced and the pistons in axial alignment with the second half of said thrust member to be progressively retracted in response to said thrust member being rotated and inclined to said shaft, the combination of two sets of hold-up motors carried by said structure and reacting against said housing, the first set and the second set being arranged in alignment with said first half and said second half of said thrust member respectively, a non-rotatable element carried by said housing and having a plurality of holes formed therein in a circular row and extending through a face thereof which constitutes a valve seat, each of said holes being arranged in substantially the same plane as one of said cylinders, a plurality of fluid channels each having one end communicating with one of said holes and its other end communicating with the cylinder in the same radial plane, a valve carried by said structure in contact with said valve seat and having formed therein upon the same radius as said row of holes a first arcuate port and a second arcuate port which are arranged respectively upon the same sides of said shaft as said first and said second halves of said thrust member and with which each of said holes registers alternately during rotation of said valve, and fluid channels connecting said first set of hold-up motors to said first port and connecting said second set of hold-up motors to said second port so that said first set of hold-up motors are supplied with liquid at the pressure prevailing in the cylinders containing advancing pistons and said second set of hold-up motors are supplied with liquid at the pressure prevailing in the cylinders containing retracting pistons.

18. In a pump having a housing, a plurality of stationary and substantially parallel pumping cylinders arranged in said housing in a circular row, a piston fitted in each cylinder, a drive shaft journaled in said housing with its axis passing through the center of said circular row, a structure fixed to said shaft to rotate therewith and including a thrust member arranged in front of said pistons in alignment therewith and adjustable to a position inclined to said shaft, a driving head arranged in front of said thrust member, and a first and a second hydraulic thrust bearing arranged between said head and the first half and the second half of said thrust member, and force transmitting means engaging said thrust member and connected to said pistons to cause the pistons in axial alignment with a first half of said thrust member to be progressively advanced and the pistons in axial alignment with the second half of said thrust member to be progressively retracted in response to said thrust member being rotated and inclined to said shaft, the combination of two sets of hold-up motors carried by said structure and reacting against said housing, the first set and the second set being arranged in alignment with said first half and said second half of said thrust member respectively, a non-rotatable element carried by said housing and having a plurality of holes formed therein in a circular row and extending through a face thereof which constitutes a valve seat, each of said holes being arranged in substantially the same plane as one of said cylinders, a plurality of fluid channels each having one end communicating with one of said holes and its other end communicating with the cylinder in the same radial plane, a valve carried by said structure in contact with said valve seat and having formed therein upon the same radius as said row of holes a first arcuate port and a second arcuate port which are arranged respectively upon the same sides of said shaft as said first and said second halves of said thrust member and with which each of said holes registers alternately during rotation of said valve, and fluid channels connecting said first set of hold-up motors to said first port and connecting said second set of hold-up motors to said second port so that said first set of hold-up motors are supplied with liquid at the pressure prevailing in the cylinders containing advancing pistons and said second set of hold-up motors are supplied with liquid at the pressure prevailing in the cylinders containing retracting pistons.

ters alternately during rotation of said valve, and fluid channels connecting said first set of hold-up motors and said first thrust bearing to said first port and connecting said second set of hold-up motors and said second thrust bearing to said second port so that said first set of hold-up motors and said first thrust bearing are supplied with liquid at the pressure prevailing in the cylinders containing advancing pistons and said second set of hold-up motors and said second set of thrust bearings are supplied with liquid at the pressure prevailing in the cylinders containing retracting pistons.

19. In a pump having a housing, a plurality of stationary and parallel cylinders arranged in said housing in a circular row, a piston fitted in each cylinder, a drive shaft journaled in said housing with its axis passing through the center of said row of cylinders, a structure fixed to said shaft to rotate therewith and including a thrust member arranged in axial alinement with said pistons and tilttable in either direction from a neutral position in which it is normal to said shaft to an operative position in which it is inclined to said shaft, force transmitting means engaging said thrust member and connected to said pistons to cause the pistons in alinement with a first half of said thrust member to be progressively advanced and the pistons in alinement with the second half of said thrust member to be progressively retracted in response to said thrust member being rotated and inclined to said shaft, said structure having formed therein two channels one of which contains liquid at the pressure prevailing in the cylinders containing advancing pistons and the other of which contains liquid at the pressure prevailing in the cylinders containing retracting pistons, and means for continuously supplying liquid at a constant low pressure to the cylinders containing retracting pis-

tons, the combination of mechanical means connected to said thrust member for tilting it in either direction from and toward its neutral position, hydraulic motor means carried by said structure and connected to said mechanical means for operating the same, means for controlling the operation of said motor means including a pilot valve carried by said structure and hydraulically connected to said motor means, means for supplying liquid through said pilot valve to said motor means including an automatic valve hydraulically connected to said pilot valve and to both of said channels and responsive to the pressure in either channel exceeding said low pressure for connecting said pilot valve to the other channel.

20. A combination according to claim 19 and including a floating lever engaging said pilot valve, a collar slideable on said shaft, means engaging said collar and said lever for moving said lever to effect movement of said pilot valve away from its neutral position in response to movement of said collar, and means connected to said lever and responsive to movement of said thrust member for moving said lever to effect movement of said pilot valve toward its neutral position.
